UNITED STATES PATENT OFFICE.

ALONZO ROLAND GOSSETT AND BERRY R. HICKS, OF HENRIETTA,
NORTH CAROLINA.

LET-OFF FOR LOOMS.

SPECIFICATION forming part of Letters Patent No. 767,937, dated August 16, 1904.

Application filed May 16, 1904. Serial No. 208,138. (No model.)

To all whom it may concern:

Be it known that we, ALONZO ROLAND GOSSETT and BERRY R. HICKS, citizens of the United States, residing at Henrietta, in the county of Rutherford and State of North Carolina, have invented certain new and useful Improvements in Let-Offs for Looms, of which the following is a specification, reference being had therein to the accompanying drawings.

This invention relates to looms, and particularly to the let-off mechanism thereof, the invention being especially applicable to those looms wherein the warp-beam is positively rotated to gradually let off the warp as the weaving progresses. The tension of the warp in such looms usually depends upon the tension of a spring which is arranged to yield when the warp tension increases and the whip-roll is depressed and to expand and raise the whip-roll and take up slack in the warp when the warp tension decreases. The spring operates to maintain a comparatively uniform tension in the warp, and the amount of movement in the whip-roll caused by a given impulse in the warp depends on the tension of the spring.

An object of this invention is to provide simple and efficient means whereby tension of the spring which governs the tension of the warp can be adjusted by the operator without leaving his position in front of the loom and whereby such adjustment can be made while the loom is in motion.

The invention contemplates the employment of an elongated gear arranged to travel on the screw-threaded part of the rod carrying the spring which governs the tension of the warp, the tension of said spring being altered by the rotation and consequent travel of the gear on the rod. Rotation of the gear is caused by rotation of a pinion which meshes therewith, said pinion being mounted on a rod or arbor which extends to the front of the loom, where it carries a hand-wheel easily accessible to the operator.

Further objects of the invention are to provide means whereby the pinion can be readily

caused to follow any extreme travel of the gear, to provide means whereby the gear and pinion can be locked in adjusted position and the spring prevented from coming out of adjustment, to provide means whereby the mesh of the gear and pinion can be easily adjusted, and to make various other improvements in devices of this character.

An embodiment of the invention is delineated for purposes of illustration in the accompanying drawings, forming part hereof, and reference to which is made hereinafter.

In the drawings like reference characters refer to corresponding parts in the several views, of which—

Figure 1 is a partial elevation of one side of a loom provided with let-off mechanism in which is included an embodiment of our invention. Fig. 2 is an enlarged detail view of the tension-rod and the various parts associated therewith. Fig. 3 is a sectional view on the line *z z*, Fig. 2. Fig. 4 is a view of the front stand of the adjusting-rod, and Fig. 5 is a view of the rear stand of the adjusting-rod.

Referring more particularly to the drawings, 1 designates the frame of the loom.

The whip-roll stand 2 has a vertical slot 3 therein, through which it is adjustably attached to the loom-frame, and this stand supports a rock-shaft 4, having thereon a carrier 5, which holds the whip-roll 6. The rock-shaft 4 is provided with a depending rocker-arm 7, to the lower end of which is pivotally connected a bent spring carrying tension-rod 8, longitudinally movable in a guide 9, fixed on the loom-frame. Rod 8 is screw-threaded from the end adjacent to rocker-arm 7 for some distance, and connection between said rod and rocker-arm is effected by a sleeve 10, which is interiorly screw-threaded and screwed on the end of the rod. The lower and shorter portion of rod 8 carries a spring 11, which is held in place between an adjustable collar 12 on the rod and the eye of a lever 13, and said eye of the lever is held on the rod by an adjustable collar 14 on the rod. A rod 15 connects lever 13 with mechanism

for transmitting positive rotative motion to the warp-beam 16 in a well-known manner, a collar 17 on rod 15 being engaged by an actuator-rod 18, connected with and operated 5 by some moving part of the loom—as the lay-sword 19, for instance.

A controlling-spring 20 is disposed on tension-rod 8 between guide 9 and an elongated gear 21 on the screw-threaded part of said 10 rod. The bore of gear 21 for part of its length, as at 22, is screw-threaded, whereby upon rotation it is caused to travel on rod 8 and alter the tension of spring 20, the tension being increased when the gear moves toward 15 guide 9 and decreased when it moves therefrom. Gear 21 is bored smooth for a portion of its length from the end adjacent to sleeve 10, as shown at 23, whereby the gear in moving in one direction along rod 8 can cover the 20 sleeve and not be unduly limited in its movement. A recess or countersink 24 is provided in the other end of gear 21, wherein is seated a collar or washer 25. Collar 25 is fastened to spring 20, provides a bearing-surface between 25 the spring and gear 21, and serves to keep the spring from contact with and consequent wear on the screw-threads of rod 8.

A pinion 26 on one end of a rod or arbor 27 meshes with gear 21, said rod being supported 30 in stand 28, near said pinion, and in stand 29. The rod extends to the front of the loom, where it carries a hand-wheel 30, the gear 21 being rotated by this mechanism and the tension of spring 20 altered. Stand 35 28 has a vertical slot therein, through which passes a bolt or screw, which secures a bearing 31 for rod 27 to said stand, whereby said bearing and said rod can be raised or lowered to cause pinion 26 to properly mesh with gear 40 21. Near hand-wheel 30 rod 27 is provided with annular grooves 32, the portion of the rod in said grooves being angular in cross-section. Stand 29 is provided with an aperture 33, through which passes rod 27, said aperture being rounded and of sufficient size at the top to permit rotative and longitudinal movement of said rod therein and squared at the bottom to fit the angular portion of the rod in annular grooves 32 to prevent both 45 rotative and longitudinal movement of the rod.

When it is desired to adjust the tension of spring 20, rod 27 is raised from the squared to the rounded part of aperture 33, where it is rotated to operate the pinion and gear and 55 secure the desired tension in the spring, and then it is lowered to the squared part of the aperture, where rotation will be prevented by the angular part of the rod, and gear 21 thereby securely locked against rotation. Where 60 the travel of gear 21 is extreme in either direction, pinion 26 can be caused to follow said gear by raising rod 27 in aperture 33 and moving it longitudinally from one of annular grooves 32 to another.

Heretofore the tension of spring 20 has usually been altered by moving a collar along rod 8 and securing it in adjusted position by a set-screw. This operation is cumbersome. It is necessary for the loom-fixer to go to the loom with a wrench or other tool to make the 70 adjustment. It is impossible to make the adjustment while the loom is in motion, and it is difficult to so set the collar to get the desired tension. By the use of our invention all these difficulties are obviated, the tension 75 of the spring being adjusted with facility by the operator at his position in front of the loom while the loom is in motion as well as when it is at rest. Further, our device has the advantage of providing an adjusting hand-wheel which is not subjected to jerky movement by the intermittent motion of its supporting means.

While one form or embodiment of our invention is disclosed and described herein, we 85 do not limit ourselves to the details of construction shown in the drawings, as it is obvious that various modifications can be made therein without in the least departing from the nature and spirit of the invention.

Having thus described our invention, what we claim as new, and desire to secure by Letters Patent, is—

1. In a loom, the combination with means whereby the whip-roll is moved, of a rod connected with said means, a fixed guide through which said rod is longitudinally movable, an elongated gear on said rod, a spring interposed between said guide and said gear, and means whereby said gear is rotated and tension of 95 said spring altered.

2. In a loom, the combination with means whereby the whip-roll is moved, of a screw-threaded rod connected with said means, a fixed guide through which said rod is longitudinally movable, an elongated gear on said rod having a screw-threaded bore, a spring interposed between said guide and said gear, and means whereby said gear is rotated and tension of 105 said spring altered.

3. In a loom, the combination with means whereby the whip-roll is moved, of a screw-threaded rod connected with said means, a fixed guide through which said rod is longitudinally movable, an elongated gear on said 115 rod having a screw-threaded bore, a spring interposed between said guide and said gear, and means extending to the front of the loom whereby said gear is rotated and tension of said spring altered.

4. In a loom, the combination with means whereby the whip-roll is moved, of a sleeve connected with said means, a screw-threaded rod having one end connected with said sleeve, a fixed guide through which said rod is longitudinally movable, an elongated gear on said rod having a bore screw-threaded near one end and smooth at the other end whereby it 125

- can travel on said rod and cover said sleeve, a spring interposed between said guide and said gear, and means whereby said gear is rotated and tension of said spring altered.
5. In a loom, the combination with means whereby the whip-roll is moved, of a screw-threaded rod connected with said means, a fixed guide through which said rod is longitudinally movable, an elongated gear on said rod having a screw-threaded bore, a collar adjacent to said gear, a spring interposed between said guide and said collar, and means whereby said gear is rotated and tension of said spring altered.
10. In a loom, the combination with means whereby the whip-roll is moved, of a screw-threaded rod connected with said means, a fixed guide through which said rod is longitudinally movable, an elongated gear on said rod having a screw-threaded bore, a collar adjacent to said gear, a spring interposed between said guide and said collar, and means whereby said gear is rotated and tension of said spring altered.
15. In a loom, the combination with means whereby the whip-roll is moved, of a screw-threaded rod connected with said means, a fixed guide through which said rod is longitudinally movable, an elongated gear on said rod having a screw-threaded bore, a spring on said rod and having one end bearing against said guide, a collar fastened to the other end of said spring and bearing against said gear, and means whereby said gear is rotated and tension of said spring altered.
20. In a loom, the combination with means whereby the whip-roll is moved, of a screw-threaded rod connected with said means, a fixed guide through which said rod is longitudinally movable, an elongated gear on said rod having a screw-threaded bore, a collar seated in a recess in the end of said gear, a spring interposed between said guide and said collar, and means whereby said gear is rotated and tension of said spring altered.
25. In a loom, the combination with means whereby the whip-roll is moved, of a screw-threaded rod connected with said means, a fixed guide through which said rod is longitudinally movable, an elongated gear on said rod having a screw-threaded bore, a collar seated in a recess in the end of said gear, a spring interposed between said guide and said collar, and means whereby said gear is rotated and tension of said spring altered.
30. In a loom, the combination with means whereby the whip-roll is moved, of a screw-threaded rod connected with said means, a fixed guide through which said rod is longitudinally movable, an elongated gear on said rod having a screw-threaded bore, a spring on said rod and having one end bearing against said guide, a collar fastened to the other end of said spring and seated in a recess in the end of said gear, and means whereby said gear is rotated and tension of said spring altered.
35. In a loom, the combination with means whereby the whip-roll is moved, of a screw-threaded rod connected with said means, a fixed guide through which said rod is longitudinally movable, an elongated gear on said rod having a screw-threaded bore, a spring on said rod and having one end bearing against said guide, a collar fastened to the other end of said spring and seated in a recess in the end of said gear, and means whereby said gear is rotated and tension of said spring altered.
40. In a loom, the combination with means whereby the whip-roll is moved, of a screw-threaded rod connected with said means, a fixed guide through which said rod is longitudinally movable, an elongated gear on said rod having a screw-threaded bore, a spring on said rod and having one end bearing against said guide, a collar fastened to the other end of said spring and seated in a recess in the end of said gear, and means whereby said gear is rotated and tension of said spring altered.
45. In a loom, the combination with means whereby the whip-roll is moved, of a screw-threaded rod connected with said means, a fixed guide through which said rod is longitudinally movable, an elongated gear on said rod having a screw-threaded bore, a spring on said rod and having one end bearing against said guide, a collar fastened to the other end of said spring and bearing against said gear and operating to keep said spring from contact with the threads of said rod, and means whereby said gear is rotated and tension of said spring altered.
50. In a loom, the combination with means whereby the whip-roll is moved, of a screw-threaded rod connected with said means, a fixed guide through which said rod is longitudinally movable, an elongated gear on said rod having a screw-threaded bore, a spring on said rod and having one end bearing against said guide, a collar fastened to the other end of said spring and bearing against said gear and operating to keep said spring from contact with the threads of said rod, and means whereby said gear is rotated and tension of said spring altered.
55. In a loom, the combination with means whereby the whip-roll is moved, of a screw-threaded rod connected with said means, a fixed guide through which said rod is longitudinally movable, an elongated gear on said rod having a screw-threaded bore, a spring on said rod and having one end bearing against said guide, a collar fastened to the other end of said spring and bearing against said gear and operating to keep said spring from contact with the threads of said rod, and means whereby said gear is rotated and tension of said spring altered.
60. In a loom, the combination with means whereby the whip-roll is moved, of a screw-threaded rod connected with said means, a fixed guide through which said rod is longitudinally movable, an elongated gear on said rod having a screw-threaded bore, a spring interposed between said guide and said gear, and means whereby said gear is rotated and tension of said spring altered.
65. In a loom, the combination with a traveling gear whereby the tension of the controlling-spring of the whip-roll is altered, of a pinion meshing with said gear, and a rod connected with said pinion and having a hand-wheel thereon whereby said gear is rotated and tension of said spring altered.
70. In a loom, the combination with a traveling gear whereby the tension of the controlling-spring of the whip-roll is altered, of a pinion meshing with said gear, and a rod attached to said pinion, said rod having means thereon whereby said gear is locked in adjusted position.
75. In a loom, the combination with a traveling gear whereby the tension of the controlling-spring of the whip-roll is altered, of a pinion meshing with said gear, a rod upon which said pinion is mounted to rotate said rod being angular in cross-section, and means coöperating with said rod whereby said gear is locked in adjusted position.
80. In a loom, the combination with a traveling gear whereby the tension of the controlling-spring of the whip-roll is altered, of a stand having a squared aperture therein, a pinion meshing with said gear, and a rod passing through the aperture in said stand and upon which said pinion is mounted to rotate, said rod being angular and arranged to seat at intervals in said squared aperture whereby said gear is locked in adjusted position.
85. In a loom, the combination with a traveling gear whereby the tension of the controlling-spring of the whip-roll is altered, of a stand having a squared aperture therein, a pinion meshing with said gear, and a rod passing through the aperture in said stand and upon which said pinion is mounted to rotate, said rod being angular and arranged to seat at intervals in said squared aperture whereby said gear is locked in adjusted position.
90. In a loom, the combination with a traveling gear whereby the tension of the controlling-spring of the whip-roll is altered, of a pinion meshing with said gear, a rod upon which said pinion is mounted to rotate and having annular grooves therein making said rod angular in cross-section at intervals, and a stand for said rod, said stand having an aperture therein enlarged and rounded at one end and smaller and squared at the other end, the rod passing through said aperture, being capable of rotative and longitudinal movements in the enlarged part thereof, and being held against such movements in the smaller squared portion thereof by the squared portion and an annular groove.
95. In a loom, the combination with a traveling gear whereby the tension of the controlling-spring of the whip-roll is altered, of a pinion meshing with said gear, a rod upon which said pinion is mounted to rotate, and means whereby said pinion can be moved longitudinally to follow the longitudinal movement of said gear.
100. In a loom, the combination with a traveling gear whereby the tension of the controlling-spring of the whip-roll is altered, of a pinion meshing with said gear, a rod upon which said pinion is mounted to rotate, and means whereby said pinion can be moved longitudinally to follow the longitudinal movement of said gear.
105. In a loom, the combination with a traveling gear whereby the tension of the controlling-spring of the whip-roll is altered, of a pinion meshing with said gear, a rod upon which said pinion is mounted to rotate, and means whereby said pinion can be moved longitudinally to follow the longitudinal movement of said gear.
110. In a loom, the combination with a traveling gear whereby the tension of the controlling-spring of the whip-roll is altered, of a pinion meshing with said gear, a rod upon which said pinion is mounted to rotate, and means whereby said pinion can be adjusted to and from said gear.

17. In a loom, the combination with a traveling gear whereby the tension of the controlling-spring of the whip-roll is altered, of a pinion meshing with said gear, a rod upon which said pinion is mounted to rotate, and an adjustable bearing for said rod whereby said pinion can be adjusted to and from said gear.

In testimony whereof we affix our signatures in presence of two witnesses.
